DESIGN FOR A LINK BRACELET

Irving Stern and Hyman Stern, Brooklyn, N. Y.

Application February 20, 1948, Serial No. 144,636

Term of patent 7 years

(Cl. D45—4)

To all whom it may concern:

Be it known that we, Irving Stern and Hyman Stern, both citizens of the United States, both residing at Brooklyn, New York, in the county of Kings and State of New York, have invented a new, original, and ornamental Design for a Link Bracelet, of which the following is a specification, reference being had to the accompanying drawing, forming a part thereof.

In the drawing:

Fig. 1 is a top plan view of a link bracelet showing my new design, the links shown in full lines being repeated throughout the length of the bracelet, as indicated by the broken lines across the center;

Fig. 2 is an enlarged view of the full line portion within the dot and dash area of Fig. 1; and

Fig. 3 is an edge elevational view of the portion shown in Fig. 2 looking in the direction of the arrows 3—3.

We claim:

The ornamental design for a link bracelet, as shown and described.
